Primary Examiner — Katie Jane Stofko(74) Attorney, Agent, or Firm — Kilpatrick Townsend & Stockton LLP(57) CLAIM

The ornamental design for a food product, as shown and described.

DESCRIPTION

FIG. 1 is a perspective view of a food product, showing our new design;

FIG. 2 is a top plan view thereof;

FIG. 3 is a front elevation view thereof the rear elevation view being identical;

FIG. 4 is a right side elevation view thereof the left side elevation view being identical; and,

FIG. 5 is a bottom plan view thereof.

The broken line portions of the food product in the drawings form no part of the claimed designs. The dash-dot-dash boundary lines form no part of the claimed design.

1 Claim, 3 Drawing Sheets(56)
